UNIVERSAL SPEED WRENCH

Filed March 24, 1947

UNITED STATES PATENT OFFICE

2,455,434

UNIVERSAL SPEED WRENCH

Nordal Mikelson, Yankton, S. Dak.

Application March 24, 1947, Serial No. 736,878

1 Claim. (Cl. 74—127)

1 My invention relates to a wrench.

An object of my invention is to provide a wrench type of tool, which includes readily adjustable means whereby the wrench can be made to turn either in a clockwise, or counter-clockwise direction as desired by merely sliding a collar attached to the device forwardly and backwardly.

A further object of my invention is to provide means whereby the tool may be used for valve grinding or similar operations, or where the tool will rotate in both directions, by using the same collar.

A further object of my invention is to provide means for attaching a variety of tools to the end of the wrench, such as a screw driver, socket wrench, drill, or other tools employing a rotary motion.

A further object of my invention is to provide the above mentioned objects in a simple construction, which can be manufactured at a reasonable cost.

With these and other objects in view, my invention consists in the construction, arrangement, and combination of the various parts of my device, whereby the objects contemplated are attained, as hereinafter more fully set forth, pointed out in my claim, and illustrated in the accompanying drawings, in which:

Figure 1 is a side elevation of the tool in its vertical position,

Figure 2 is a sectional detail of the sleeve handle,

Figure 3 is a further detail,

Figure 4 is a detail looking at the rear of Figure 3,

Figure 5 is a detail showing the attaching clip attached to the unit, and

Figure 6 is a detail of the attaching clip.

I have used the character 10 to designate an upper handle portion including a pin 11 received in an annular slot 12 which slot is formed in the extended portion 13 of the member 14, the portion 13 being freely revolvable within the handle 10.

Rigidly attached at 15 to the portion 14 is the substantially lengthened rod 16 which includes the spiral pitched threads 17. The member 16 terminates at 18 in a U-shaped portion 19 having the recess 20. Mounted within the recess 20 is a member 21, a pin 22 securing the member 21 to the portion 19. A small spring urged ball 23 is normally used to bear against a depression in the member 21 to lock it in place after the necessary tool is installed. The member 21 extends into the portion 24 which includes a further small

5 spring urged ball 25 to firmly receive and engage the socket portion 26 of the tool to be used, and attached to the portion 26, is in one instance as shown, the socket wrench 27 having the usual hexagon, or square depression 28 to properly engage a bolt or nut.

Other tools can be used with the arrangement, and as will be explained later, such as the valve grinding tool 29 having the valve grinding prongs 30, such being attached to the same type of socket 26, and being attached to the tool as above described. The character 31 indicates a twist drill, and the character 32 a screw driver, these tools being attached to the socket as shown.

10 A cylindrical handle sleeve 33 includes a pair of members 34 attached interiorly thereof, and at the ends thereof, by means of suitable screws 35, the members 34 including the ratchet teeth 36 in opposed relation to each other as shown in Figure 2. A further member 37 is engaged at 33 with the pitched spiral threads 17, and the member 37 includes ratchet teeth 39 which are adapted to engage the teeth 36. The member 37 also includes an annular channel 40.

15 Attached at 41 by means of screws or any other suitable method is an arcuate plate 42 which includes an opening 43 having the end notches 44 and a central notch 45. A slideable keeper member (see Fig. 3) 46 is positioned beneath the arcuate plate 42 and includes the outwardly extending pin 47 adapted to be received within any one of the notches 44 or 45. A spring 48 is attached at 49 directly to the member 42 and includes a portion 50 bearing against the member 46, yet allowing the member 46 to be placed in any desired position due to the slideable action of the member 46 with respect to the portion 50. The member 46 includes a downwardly extending boss 51 which normally is adapted to be received within the channel 40 of the member 37, and yet being of smaller diameter than the width of the channel 40 to allow the ratchet to engage in one direction and release in the other.

20 The outer sleeve 33 also includes an opening 52 (see Fig. 4) which is directly opposite to the arcuate plate 42 or at the other side of the sleeve. The opening 52 is adapted to communicate with a further opening 53 which opening 53 is within the channel portion 40 and extends through the same. An arcuate spring member 54 in some cases as will later be explained is adapted to snugly engage the sleeve 33, and includes a pin 55 which passes through the opening 52 and into the opening 53.

25 The device is used in the following manner. In

operating the tool, the handle 10 is held with one hand while the sleeve 33 is held with the other hand, and this sleeve 33 is reciprocated back and forth along the rod 16. For obtaining rotation in either direction, the small pin 47 is placed in either one of the notches 44. For instance, as shown in Figures 1 to 3 inclusive, the pin 47 has been placed in the lower-most notch 44. This correspondingly brings the lower teeth 39 of the ratchet in engagement with the teeth 36 of the lower member 34. Since the spiral threads 17 of the rod 16 are engaged with the member 37; as the sleeve 33 is reciprocated back and forth along the rod 16, the rod 16 will turn in one direction only during one part of the stroke but will be released in the other direction during the other part of the stroke. This releasing action will occur since the boss 51 is slightly smaller as explained than the width of the channel 49 which allows the teeth 39 and 36 to become disengaged during the reverse action, but firmly grips and rotates the tool during the other stroke. It will be understood that the movement of the pin 47 carries the keeper 46 and the boss 51 with which to move the above mentioned member 37.

When it is desired to obtain rotation in the other direction only, the pin 47 is placed in the upper notch 44, bringing the upper ratchet teeth 39 and 36 into engagement, the reciprocating movement of the sleeve 33 causing the power rotation to be effected in the opposite direction as will be evident from the engagement of the members. In one instance, the power will be applied during forward motion of the sleeve and in the other instance during rearward motion.

By virtue of this construction any of the tools shown in Figure 1 with the exception of the valve grinder, can be used for turning clockwise or counter-clockwise as desired. This makes the tool readily applicable for a variety of desired conditions such as right and left hand threads, etc.

For obtaining movement of the tool in both directions during slidable action of the sleeve 33, the pin 47 is placed in the central notch 45 which carries the member 37 into a neutral position, or out of engagement with any of the ratchet teeth. Next, the arcuate spring member 54 is snapped on to the sleeve 33 so that the pin 55 engages into the openings 52 and 53, which correspondingly locks the member 37 against rotation with respect to the sleeve 33. Then, when the sleeve is thrust forwardly and backwardly along the rod 16, the engagement of the twisted threads 17 with the member 37 will cause the rod to rotate in one direction during one portion of the stroke and in the reverse direction during the reverse stroke. For this operation, the valve grinding tool 29 can

be used, or any other tool requiring this type of motion.

It will now be seen that I have provided all of the various advantages mentioned in the objects 5 of my invention with further other advantages being readily apparent.

Some changes may be made in the construction and arrangement of the parts of my invention without departing from the real spirit and purpose of my invention, and it is my intention to cover by my claim any modified forms of structure or use of mechanical equivalents which may be reasonably included within their scope.

I claim as my invention:

15 A tool of the character described, comprising a handle, a lengthened rod having a spiral thread thereon, a further handle engaged with said spiral thread adapted to move said rod in selected direction during reciprocating motion thereof along said rod, said further handle including means for controlling direction of power applied to said rod including a pair of stationary ratchet members attached to said further handle, a rotatable ratchet member received in said further handle member, said spiral thread engaged with said rotatable ratchet member, means for locking said rotatable ratchet member with either of said stationary ratchet members as desired to provide selected direction of rotation of the tool, including 20 a guide plate engaged with said rotatable ratchet member, said further handle including notches, said guide plate including an extended pin received in any of said notches, end notches providing means for securing said rotatable ratchet against either of said stationary ratchets, one of said notches providing a neutral notch, said 25 neutral notch providing means for maintaining said rotatable ratchet out of engagement with either of said stationary ratchets, means for securing said normally rotatable ratchet against 30 rotation to provide rotation in both directions of the tool during reciprocating action of said further handle, said means including a spring clip adapted to snugly receive said further handle member, a pin attached to said spring clip, openings in said further handle and said normally rotatable ratchet for receiving said pin.
